UNITED STATES PATENT OFFICE.

CHARLES H. CARROLL, OF TAMPA, FLORIDA.

RAIL-JOINT.

1,220,184.

Specification of Letters Patent. Patented Mar. 27, 1917.

Application filed May 13, 1916. Serial No. 97,375.

To all whom it may concern:

Be it known that I, CHARLES H. CARROLL, a citizen of the United States, residing at Tampa, in the county of Hillsboro and State 5 of Florida, have invented certain new and useful Improvements in Rail-Joints, of which the following is a specification.

This invention relates to a rail joint and more particularly to a novel manner of joining the meeting ends of two railway rails whereby the spreading of the rails or the lateral displacement thereof with respect to the longitudinal alinement of the rail will be prevented.

15 As a further object of the invention the rail ends are provided with obliquely disposed contacting surfaces formed by vertically cut portions of the rail ends thereby obviating the occurrence of the constant and 20 injurious impact which occurs when the wheels of a railway coach pass over the meeting ends of rails.

I further purpose to improve the manner 25 of joining the meeting ends of railway rails by providing the inside half of the base flange of the rail with a right angularly vertical cut portion for providing meeting faces in each rail in addition to the obliquely disposed contacting surfaces thereby preventing 30 relative longitudinal movement of the rails and lateral displacement thereof.

The above and additional objects are accomplished by such means as are illustrated 35 in the preferred embodiment and in the accompanying drawings, wherein like characters denote like or corresponding parts throughout the several views, in which:—

Figure 1 is a top plane.

Fig. 2 is a vertical transverse section on 40 the line 2—2 of Fig. 1.

Fig. 3 is a perspective view showing the manner of connecting one of the rail ends.

Fig. 4 is a perspective view of the adjacent end.

45 The meeting ends of two railway rails are designated by the numerals 1 and 2 and each of the rails is provided with the rail head 3, the web 4 and the base flange 5. The base flange 5 extends outwardly from 50 opposite sides of the web in the usual manner whereby the inside half 6 and the outside half 7 of each flange is provided.

The head 3, the web 4 and the outside half 7 of the flange of each rail are cut vertically and diagonally as is clearly shown in 55 the drawings to provide the obliquely dis-

posed surfaces 8 and 9. The inside half 6 of the base flange is vertically cut at right angles to the longitudinal center line of the rail and the cut extends inwardly from the 60 edge of the flange to the edge of the web 4 where it joins the obliquely disposed surfaces 8 and 9. This right angularly cut portion provides the right angularly disposed contacting surfaces 10 and 11 which, when 65 in engagement with each other, prevent the rail ends from relative longitudinal "movement" which otherwise would occur if the rail ends were simply provided with the obliquely or diagonally cut ends. By referring to Figs. 3 and 4 of the drawing it will be observed that a sharp corner is provided where the obliquely disposed surfaces join with the right angular surfaces thus permitting the rail ends to neatly join or lock together in which position they may be securely fastened.

Each of the rails is provided with a plurality of apertures 13 extending through the webs 4 and a fish plate 14 is mounted upon 80 each side of the web 4. Each of the fish plates is provided with a plurality of apertures through which fastening bolts 15 are extended and have nuts 16 mounted on their ends for retaining the fish plates in tight 85 engagement with the webs of the rails. The fish plates 14 overlap the meeting ends of the rails and extend for a considerable distance on each side thereof for assuring the connection of the rail ends.

In reduction to practice I have found that the form of my invention illustrated in the drawings and referred to in the above description, as the preferred embodiment, is the most efficient and practicable; yet realizing that the conditions concurrent with the adoption of my device will necessarily vary, I desire to emphasize the fact that various minor changes in the details of construction, proportion and arrangement of 100 parts may be resorted to, when required, without sacrificing any of the advantages of my invention, as defined in the appended claims.

I claim:

1. In a rail joint, two rails each comprising a rail head, web and base flange, the meeting end of each rail cut vertically diagonally through the said head, web and the outside half of said base flange, the diagonal cut portions being identical in each rail end and adapted to engage for prevent-

105

110

ing longitudinal movement of the rail ends out of longitudinal alinement with each other, said base flange being further vertically cut at right angles to the longitudinal center line of the rail, the right angularly vertically cut portion of said base flange extending from the inner edge of the inner half of said flange and terminating in a sharp corner at the edge of the web of the rail where said vertically cut portion joins with the diagonally cut portion of said web.

2. In a rail joint, the combination with the meeting ends of two railway rails, each comprising a head, a web and a base flange, said base flange extending outwardly equally on each side of the web to provide inside and outside halves of said base flange, the said head, web and outside half of the flange being cut vertically diagonally in each rail for providing obliquely disposed contacting surfaces adapted to engage and prevent the lateral displacement of said rail ends with respect to their true longitudinal alinement, the said inside half of the base flange in each rail being further cut vertically at right angles to the longitudinal center line of the rail for providing right angularly disposed meeting faces extending inwardly from the edge of the rail and terminating at the edge of the web, fish plates mounted upon the web and overlapping the meeting ends of each rail, and a plurality of bolts

carried by the fish plates and extended through apertures formed in the web for fastening the said fish plates in position.

3. In a rail joint, the combination with the meeting ends of two railway rails, each comprising a head, a web, and a base flange, the said head, web and outside portion of the said flange being cut vertically diagonally in each rail providing obliquely disposed contacting surfaces adapted to engage and prevent the lateral displacement of the said rail ends with respect to their true longitudinal alignment, the inside half of the base flange in each rail being cut vertically at right angles to the longitudinal center line of the rail for providing right angularly disposed meeting faces adapted to contact, the angularly cut portion of the said head directly above the said inside half of the flange permitting the corresponding ends of the said flanges to be moved vertically into and out of contact with each other, the said vertical cut portion of the inside half of the flange extending from the edge thereof to the edge of the said web. 40 45 50 55

In testimony whereof I affix my signature
in presence of two witnesses.

CHARLES H. CARROLL.
